CLAIM

The ornamental design for a foldable handle for electric grill as shown and described.

DESCRIPTION

FIG. 1 is a front, bottom perspective view of a foldable handle for electric grill showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, top perspective view thereof;

FIG. 9 is an enlarged detail view taken from portion 9 of FIG. 1;

FIG. 10 is an enlarged detail view taken from portion 10 of FIG. 1;

FIG. 11 is an enlarged detail view taken from portion 11 of FIG. 3; and,

FIG. 12 is an enlarged detail view taken from portion 12 of FIG. 8.

The evenly-dashed broken lines show portions of the foldable handle for electric grill that form no part of the claimed design. The dot-dash broken lines depict the boundary of the enlarged views and form no part of the claimed design.

1 Claim, 12 Drawing Sheets
